UNITED STATES PATENT OFFICE.

THOMAS FREEMAN, OF TORONTO, ONTARIO, CANADA, ASSIGNOR OF ONE-HALF TO JOHN FITZALLEN ELLIS, OF SAME PLACE.

COMBINED BACKING, PLOWING, AND GILDING PRESS.

SPECIFICATION forming part of Letters Patent No. 323,313, dated July 23, 1885

Application filed September 22, 1884. (No model.) Patented in Canada September 24, 1884, No. 20,258.

To all whom it may concern:

Be it known that I, THOMAS FREEMAN, of the city of Toronto, in the county of York, in the Province of Ontario, Canada, book-binder, 5 have invented a certain new and useful Combined Backing, Plowing, and Gilding Press; and I do hereby declare that the following is a full, clear, and exact description of the same.

This invention relates to combined backing, 10 plowing, and gilding presses; and the novelty consists in the peculiar combinations and the construction and arrangement of parts, herein-after more fully described, and then specifically pointed out by the claims.

15 Figure 1 is a perspective view of the machine as it appears when employed for holding the book for backing. Fig. 2 is a similar view of the machine when employed for holding the book for plowing. Fig. 3 represents the machine when employed for holding the books 20 for gilding.

In the drawings like letters of reference indicate corresponding parts in each figure.

A represents a rectangular frame suitably 25 journaled in the standards B, which are designed to rest upon the floor, and are made the proper height for the convenience of the operator.

30 C is a pin inserted through the journal at each end of the frame A, so that the said frame shall be held in a horizontal position as long as the pins remain inserted; but by the removal of the pins the said frame may be turned within the journal when it is required to be so moved.

35 D is a cross-head carried in suitable guides formed on the side pieces of the frame A. This cross-head D is attached to and operated by the screw E, which passes through a nut 40 formed in the end of the frame A, and is provided with a suitable wheel or handle, F.

G is a table screwed on top of the frame A, and forming a resistance-plate, between which and the cross-head D the article to be pressed 45 may be placed.

When the machine is to be employed for holding the book during the process of backing, I place cheek-blocks H in the position shown in Fig. 1, one block being fixed to the 50 edge of the table G, while the other block is similarly attached to the cross-head D.

When the machine is to be employed for plowing, the cheek-blocks H are removed and the guide-bars I placed in the position shown in Fig. 2, the said guide-bars I being intended 55 for the purpose of holding the plow in position during the period that it is employed in finishing the edge of the book, J, shown in this figure.

In addition to the table G, which is detachably fixed in the position shown, I employ a similar table, K, attached to the cross-head D. Both these tables are removed when the machine is to be employed for holding the books J when it is desired to gild their edges. 60 65 The ends of the frame A have guide-pieces formed on them to receive and hold a board, L, made any desired width, and designed to support the books during the period that they are being arranged between the cross-head D 70 and the end of the frame A.

When the machine is to be employed as a gilding-press, as shown in Fig. 3, the tables G and K are, as before stated, removed and the pins C withdrawn, when the frame A may 75 be turned in its journal, so as to bring the board L, which has been inserted, in position at the bottom of the frame A, in order that the books, J, to be gilded may be arranged evenly on the said board, after which they 80 are gripped securely by the cross-head D, and the books easily got at by turning the frame A on its journal, so that by this invention not only is a convenient apparatus produced for plowing and backing, but the frame may be 85 readily reversed to insert the books, and then again reversed to gild their edges.

I am aware of the Patent No. 242,972, and make no claim to the construction shown therein as forming part of my invention. 90

What I claim as my invention is—

1. A rectangular frame, A, provided with a detachable table, G, having one of the cheek-blocks H fixed to its inner edge, in combination with the cross-head D, also having a 95 cheek-block, H, fixed to it and operated by the screw E, substantially as and for the purpose specified.

2. A rectangular frame, A, provided with a detachable table, G, having holes to receive 100 guide-bars, and having a cheek-block, H, detachably fixed to its inner edge, in combina-

tion with the cross-head, also carrying a cheek-block, H, and the screw E, for operating said cross-head, substantially as and for the purposes specified.

5 3. In a device for the purposes described, the combination, with the standards B, having bearings on substantially the same horizontal plane, of the rectangular frame A, journaled in said standards, the adjustable cross-head D, carried in said frame, and the screw E, passing

through one of said standards and through a nut formed in the end of the frame and operating on said cross-head, substantially as and for the purpose specified.

Toronto, August 28, 1884.

THOS. FREEMAN.

In presence of—

CHARLES C. BALDWIN,
JAS. E. MAYBEE.
